UNITED STATES PATENT OFFICE.

HERMAN JAWORSKI, OF NEW HAVEN, CONNECTICUT, ASSIGNOR TO
SARGENT & CO., OF SAME PLACE.

DESIGN FOR FLUSH-BOLT.

SPECIFICATION forming part of Design No. 11,678, dated March 9, 1880.

Application filed December 31, 1879. Term of patent 14 years.

To all whom it may concern:

Be it known that I, HERMAN JAWORSKI, of New Haven, in the county of New Haven and State of Connecticut, have invented a new Design for Flush-Bolt; and I do hereby declare the following, when taken in connection with the accompanying drawing and the letters of reference marked thereon, to be a full, clear, and exact description of the same, and which

said drawing constitutes part of this specification, and represents a face view broken into three divisions.

This invention relates to a design for the plate of the class of bolts known to the trade as "flush-bolts"—that is to say, such as are set into a recess cut in the door, and so as to hide the mechanism of the bolt; and the design consists in the ornamentation of the plate, as shown in the accompanying illustration.

From the end *a* to the point *b* constitutes the first or principal section of the bolt. Around the edge is a plain band forming a panel, and about midway of the length of this section is a cross-bar, *c*. On the face of the lower panel and around the knob-seat are two segment-shaped bars, concentric with the knobs. These are both ornamented, as shown. Below the bar *c* is an ornamented quadrant. Between the segment, around the knob-seat and the said quadrant, are two vertical ornamented bars, each having a semicircular ornament projecting onto the face of the panel. Above the bar *c*, and in the angle formed by it, is a quadrant-shaped ornament. Above this is another ornamented transverse bar, *d*, with a quadrant-shaped ornament in the angle below. Above the bar *d* is a circular or rose-shaped ornament.

The ornamental portions are raised so as to appear in relief.

This section, from *a* to *b*, constitutes the essential feature of the design, as this section may be used alone for a short bolt.

A second section, extending from *b* to *f*, has a similar border to the first section, with a diagonal ornamented bar at its lower end, and at the upper end a reverse diagonal bar, with the space between that and the angle filled with block-work. The next section, from the bar *f* to the bar *g*, has a series of points projecting

from one edge inward, and on the opposite edge a branch, with a star-shaped boss near the upper end. The next section, from *g* to *h*, has also a similar border, and also the section from *h* to *i*, each section ornamented, as shown.

These sections are used according as the first section is required to be lengthened.

I claim—

1. The design for a flush-bolt face-plate, 60 ornamented as shown, from *a* to *b*—that is to say, with a band around the edge, forming a panel on the face, segment-shaped ornamented bars around the knob-seat, ornamented transverse bars *c*, ornamented quadrant below, or- 65 ornamented vertical bars below said quadrant, a quadrant-shaped ornament above the bar *c*, transverse bar *d*, with quadrant-shaped ornament below and the rose-shaped ornament above, as shown in the accompanying illus- 70 tration.

2. The design for flush-bolt face-plate, consisting of the ornamented section from *a* to *b*, combined with the section from *b* to *f*, having a border similar to the first section, with di- 75 agonal ornaments at the lower end and a re- versed diagonal ornament above it, and orna- mentation on the face of the panel, as shown.

3. The design for flush-bolt, consisting of the ornamented section from *a* to *f*, combined 80 with the ornamented section from *f* to *g*, hav- ing the border continued and the series of or- namented points at one edge and a floriated branch at the opposite edge, as shown in the accompanying illustration.

4. The design for flush-bolt, consisting of the sections *a* to *g*, combined with the section *g* to *h*, the border continued, and the panel ornamented, as shown in the accompanying illustration.

5. The design for flush-bolt, consisting of the sections *a* to *h*, as shown, combined with the section *h* to *i*, the border continued, and the face of the panel ornamented, as shown in the accompanying illustration.

HERMAN JAWORSKI.
